UNITED STATES PATENT OFFICE.

VINCENT P. GALLE, OF FREEMANSBURG, PENNSYLVANIA.

FLYING-MACHINE.

1,257,212.

Specification of Letters Patent. Patented Feb. 19, 1918.

Application filed June 1, 1917. Serial No. 172,830.

To all whom it may concern:

Be it known that I, VINCENT P. GALLE, a citizen of the United States, residing at Freemansburg, in the county of Northampton and State of Pennsylvania, have invented new and useful Improvements in Flying-Machines, of which the following is a specification.

This invention relates to flying machines and particularly to means for automatically maintaining the lateral stability or equilibrium of the machine.

The object of the present invention is to provide in connection with the lateral balancing surfaces or planes, novel connecting means between said lateral balancing surfaces and the operator's seat, and so mount said seat, that the latter is adapted to move toward the low side of the machine and thereby operate the lateral balancing surfaces automatically in such a manner as to effect a restoration of the equilibrium of the machine, the result being accomplished automatically and without any attention or thought on the part of the occupant or occupants of the seat.

A further object of the invention is to provide in conjunction with the connecting means between the operator's seat and the lateral balancing planes, adjustable means for limiting and varying the amplitude of movement of said connecting means according to the will or desire of the aviator.

With the above and other objects in view, the invention consists in the novel construction, combination and arrangement of parts, herein described, illustrated and claimed.

In the accompanying drawings:—

Figure 1 is a plan view of a flying machine, partly broken away to show the applied relation of this invention.

Fig. 2 is a front elevation of the same.

Fig. 3 is a side elevation of the machine.

Fig. 4 is an enlarged fragmentary rear elevation partly in section showing the seat structure and part of the lateral controlling means.

Fig. 5 is an enlarged fragmentary vertical section through one of the medial struts and one of the thimbles.

In illustrating the present invention, I have shown the improved balancing means applied to a biplane structure, comprising the top and bottom planes 1 and 2, the struts 3 and diagonal stays 4, the arrangement be-

ing similar to the present day biplane construction.

In carrying out the present invention, the aviator's seat 5 is mounted so that it is laterally movable, being shown as mounted directly upon the lower plane 2. The seat 5 is mounted so as to slide lengthwise of the bottom plane or laterally with respect to the line of flight of the machine so that when the machine dips or inclines to one side, said seat will slide toward the low side.

Located above the seat 5 and parallel to the top and bottom planes is a longitudinally movable plunger rod 7 which is slidable through openings 8 in the adjacent struts or posts 3, the latter being made somewhat heavier than the remaining struts of the biplane structure in order to support and guide the necessary parts of the connecting means between the seat 5 and the ailerons or lateral balancing planes 9. Thimbles or tubular housings 10 are secured to the outer sides of the medial struts 3, being formed with attaching flanges 11 for that purpose and the outer ends of said thimbles are closed and contain cushioning springs 12 against which the opposite extremities of the plunger rod 7 bear, the springs 12 therefore serving to yieldingly resist the reciprocatory movements of said plunger rod. The seat 5 is connected to the plunger rod 7 by stays or rods 13 having slotted ends 14 which engage pins 15 on the rod 7.

Stops 16 in the form of sleeves or collars are placed around the rod 7 and provided with set screws 17 by means of which said stops may be adjusted longitudinally of the rod 7 and fastened securely thereto. The rod 7 is graduated as indicated at 18 to enable the aviator, preparatory to any particular flight, to accurately adjust the stops 16 and thereby proportionately limit the reciprocatory movements of said plunger rod.

Each of the medial struts 3 is formed with a vertically elongated recess 19 extending above and below the opening 8 through which the plunger rod 7 slides. Arranged above and below the rod 7 in the recesses 19 are bearing heads 20 carrying rollers 20' which are pressed against the opposite sides of the rod 7 by means of coiled expansion springs 21 which press against the bearing heads 20. The spring thrust bearing heads 20 serve to flexibly support the rod 7 where it passes slidably through the struts and

prevent said rod from binding in the openings 8. The bearing heads 20 also frictionally but yieldingly resist the back and forth movements of the rod 7 which controls the 5 ailerons or lateral balancing planes or surfaces.

The stays or rods 13 converge toward their lower extremities where they are connected by a pin 24 to a vertically movable plunger rod 25 movable vertically in a tubular housing or guide 26 having an attaching plate or flange 27 enabling the same to be secured by fastening means such as bolts 28 to the bottom plane 2. The bolts 28 also pass through 10 a plate 29 bearing against the under side of the bottom plane 2. The lower end of the tubular guide 26 is closed by a head 30 having a central opening to guide the plunger rod 25. Within the tubular guide 26 there 15 is arranged a compression spring 31 which is interposed between the head 30 at the bottom of the tubular guide 26 and a collar 32 fast on said plunger rod. The seat 5 is adapted to move or rock laterally on the pin 20 24 which therefore forms a pivotal connection between the seat 5 and the plunger rod 25. The spring 31 yieldingly resists the 25 downward movement of the plunger rod 25. As the seat 5 rocks to one side or the other, 30 the slotted ends 14 thereof are correspondingly moved, engaging and sliding in relation to the pins 15 of the reciprocating rod 7 so that the latter is moved in the direction of its length for the purpose of operating the 35 lateral balancing planes or ailerons.

From the foregoing description taken in connection with the accompanying drawings its will now be understood that when the flying machine lists or dips to one side or 40 the other, the seat 5 assisted by the weight of the occupant or occupants thereof will immediately swing toward the low side of the machine and by reason of the fact that said seat is attached to the plunger rod 7, 45 the latter will be actuated in the same direction, the movements thereof being yieldingly resisted by means of one of the springs 12 and also by the frictional resistance of the yieldably supported bearing heads 20. 50 The connections or cables 23 which extend from reduced extensions 22 of the plunger rod 7 to the lateral balancing planes, will thereupon perform their function, causing the balancing plane at the lower side of the 55 machine to produce a lifting effect, and the balancing plane at the higher side of the machine to produce a depressing effect. The lateral balance or equilibrium of the machine is thus automatically restored without 60 any thought or attention on the part of the aviator.

I claim:—

1. Lateral balancing means for flying machines, comprising in combination, a flying 65 machine structure, a laterally movable seat,

lateral balancing surfaces, a plunger rod in parallel and spaced relation to the supporting surface of the machine slideable longitudinally and supported by the medial struts, connecting means between the seat and said 70 plunger rod whereby the plunger rod is actuated by the lateral movements of the seat, connecting means between said plunger rod and the lateral balancing surfaces, and means for yieldingly resisting the longitudinal movements of said plunger rod. 75

2. Lateral balancing means for flying machines, comprising in combination, a flying machine structure, a laterally movable seat, lateral balancing surfaces, a plunger rod in 80 parallel and spaced relation to the supporting surface of the machine slideable longitudinally and supported by the medial struts, connecting means between the seat and said plunger rod whereby the plunger rod is 85 actuated by the lateral movements of the seat, connecting means between said plunger rod and the lateral balancing surfaces, means for yieldingly resisting the longitudinal movements of said plunger rod, and adjustable means for regulating the amplitude 90 of movement of said plunger rod.

3. Lateral balancing means for flying machines, comprising in combination, a flying machine structure, a laterally movable seat, 95 lateral balancing surfaces, a plunger rod in parallel and spaced relation to the supporting surface of the machine slideable longitudinally and supported by the medial struts, connecting means between the seat and said 100 plunger rod whereby the plunger rod is actuated by the lateral movements of the seat, connecting means between said plunger rod and the lateral balancing surfaces, means for yieldingly resisting the longitudinal 105 movements of said plunger rod, said plunger rod resisting means embodying tubular housings attached to said struts and receiving the ends of the plunger rod, and cushioning springs in said housings which 110 yieldingly take the thrust of said plunger rod.

4. Lateral balancing means for flying machines, comprising in combination, a flying machine structure, a laterally movable seat, 111 lateral balancing surfaces, a plunger rod in parallel and spaced relation to the supporting surface of the machine slideable longitudinally and supported by the medial struts, connecting means between the seat 12 and said plunger rod whereby the plunger rod is actuated by the lateral movements of the seat, connecting means between said plunger rod and the lateral balancing surfaces, means for yieldingly resisting the 12 longitudinal movements of said plunger rod, and resiliently supported bearing members between which said plunger rod is slideable.

5. Lateral balancing means for flying machines, comprising in combination, a flying 13

machine structure, a laterally movable seat, lateral balancing surfaces, a plunger rod in parallel and spaced relation to the supporting surface of the machine slidable longitudinally and supported by the medial struts, connecting means between the seat and said plunger rod whereby the plunger rod is actuated by the lateral movements of the seat, connecting means between said plunger rod and the lateral balancing surfaces, means for yieldingly resisting the longitudinal movements of said plunger rod, and resiliently supported bearing members between which said plunger rod is slidable, said bearing members being housed within the struts through which said plunger rod is slidable.

6. Lateral balancing means for flying machines, comprising in combination, a flying machine structure, a laterally movable seat,

lateral balancing surfaces, a plunger rod in parallel and spaced relation to the supporting surface of the machine slidable longitudinally and supported by the medial struts, connecting means between the seat and said plunger rod whereby the plunger rod is actuated by the lateral movements of the seat, connecting means between said plunger rod and the lateral balancing surfaces, means for yieldingly resisting the longitudinal movements of said plunger rod, said plunger rod being graduated, and stop sleeves surrounding said plunger rod and adjustable along the graduated portions thereof toward and away from said struts, said stop sleeves serving to limit the longitudinal movements of the plunger rod by contact with said struts.

In testimony whereof I affix my signature.
VINCENT P. GALLE.
